Application May 25, 1929, Serial No. 365,869

16 Claims. (Cl. 261—46)

The invention relates generally to carburetors and the primary object of the invention is to provide a carburetor of simple design capable of being economically manufactured and efficiently operated to increase the overall efficiency and controllability of the motor with which it is used.

The present invention finds its greatest usefulness when applied to a carburetor for the internal combustion motor of an automobile, for in order to meet the requirements of such service, a motor must be easily controlled and capable of gradual acceleration under load throughout practically its entire range of speeds. Such motors must also be economical of fuel in order to render their performance fully satisfactory.

The attainment of these results with a particular motor is dependent to a great extent upon the thoroughness of the vaporization of the fuel as well as upon the richness of the fuel mixture supplied to the motor at its various speeds.

In practice the fuel discharge orifice is annular in form and is positioned within a comparatively small annular chamber formed in the fuel discharge member so that the mixing of the air and fuel is initiated within this chamber. At the lower motor speeds, the air is directed past only a small arcuate section of the fuel discharge orifice so that fuel is drawn into the annular chamber and there mixed with the air and discharged into the main body of the carburetor for further mixing with air so as to form a comparatively "lean" fuel mixture. As the motor speed is increased, air is directed past a progressively increasing number of other small arcuate sections of the fuel discharge orifice to draw more fuel into the annular chamber. Thus the mixing of fuel and air continues within the chamber and gradually spreads around the same, at the same time increasing gradually in the quantity mixed in each portion of the chamber due to the increase in air velocity. This provides for a progressive expansion or growth of the mixing zone as the motor speed is increased so that smoothness of motor operation is inevitably attained.

Another object of the present invention is to provide a carburetor wherein the liquid fuel is subjected to substantially the same mixing or vaporizing action throughout the range of motor speeds.

Another object is to provide a carburetor having a plurality of different paths along which air may pass to draw fuel into the carburetor together with means for directing air along varying numbers of these paths whereby to increase or decrease the quantity of liquid fuel supplied.

Another object is to provide a carburetor having a comparatively small chamber in which the air and fuel are initially mixed together with means to control the supply of fuel and the passage of air through the chamber so that the mixing continues therein and progressively increases or spreads to different parts of the same chamber as the motor speed is increased so as to supply a uniformly increasing quantity of thoroughly mixed fuel to the motor.

Another object of the invention is to provide a carburetor embodying a fuel discharge member having a mixing chamber therein and a plurality of ducts leading therefrom arranged to be controlled and brought into operation in varying numbers through the action of the sections of compression and expansion in a venturi, this result being obtained by mounting the fuel discharge member and the venturi for relative movement longitudinally of the venturi, and arranging the ducts so as to terminate at points spaced longitudinally of the venturi.

With such a construction it will be apparent that the quantity of fuel drawn into the carburetor for any relative positioning of the fuel discharge member and the venturi is controlled by the number of ducts terminating on the expansion side of the Venturi throat, and this fact renders the construction particularly advantageous since it permits the designer accurately to control the proportioning of fuel and air at the various motor speeds. Thus if a particular motor operates more efficiently at a given speed when the proportion of fuel to air is reduced, the ducts may be spaced to give this result.

Another object is to provide a carburetor having a mixing chamber wherein mixing of air and fuel is obtained in the same manner when the carburetor is "choked", when its parts are set for idling the motor, and when parts are being moved to accelerate the motor.

More particularly I aim to provide a carburetor having a fuel discharge member, means providing a primary air supply arranged initially to mix with the fuel, means providing a secondary air supply for reducing the richness of the fuel mixture provided by mixing the fuel with the primary air, and a single control member or throttle operable positively to govern the relative amounts of fuel, primary air and secondary air, the fuel discharge member having a plurality of supply ducts of varying lengths fed from a single fuel source and brought into operation as fuel passages in varying numbers as the supply of primary air is varied by the control member.

Another object is to provide a carburetor embodying means to offset or equalize the effect of the motor suction on the throttle so that the movement of the throttle may be easily and accurately controlled by the operator.

In the lower range of motor speeds it is usually desirable to provide for an exceedingly gradual acceleration. The throttle or control member of the carburetor is usually actuated by the operator through a manual or foot-operated accelerator and it is often quite difficult for the operator to impart slight movement or very slow movement thereto. This results in an irregular acceleration of the motor. Another object of the invention is to provide a carburetor having means for actuating the throttle arranged to move the throttle very little for a given movement of the accelerator in the lower range of speeds and arranged so that the relative amount of throttle movement increases as the accelerator is moved to its most advanced position.

Other objects and advantages will become apparent from the following description taken in connection with the accompanying drawings in which:

25 Figure 1 is a vertical central section through a carburetor embodying the preferred form of the invention taken along the line 1—1 of Fig. 2.

Fig. 2 is a transverse vertical section taken along the line 2—2 of Figs. 1 and 7.

30 Fig. 3 is an enlarged fragmental section of the fuel discharge member and the sliding throttle sleeve taken along the line 1—1 of Fig. 2.

Fig. 4 is a sectional view similar to Fig. 3 showing an alternative form of the fuel discharge member and throttle sleeve.

Fig. 5 is an enlarged sectional view taken along the line 5—5 of Fig. 4.

Fig. 6 is a side elevational view of the carburetor, part in central section.

40 Fig. 7 is a plan view of the carburetor with portions of the body broken away to show the internal construction.

Fig. 8 is a diagrammatic view showing an exemplary arrangement of the fuel discharge ducts 45 in the fuel discharge member.

Fig. 9 is a section through the fuel discharge member at the fuel level.

While I have shown in the accompanying drawings and will herein describe in detail the preferred embodiment of the invention together with one alternative form thereof, it is to be understood that this disclosure is given for the purpose of illustrating the invention and is not intended as a limitation of the invention to the 55 construction disclosed. In the appended claims, I aim to cover all modifications and alternative constructions falling within the spirit and scope of the invention.

In the form chosen for disclosure herein, the 60 invention is embodied in a carburetor having a hollow body 10 providing a chamber 11 which has an intake opening 12 communicating with the atmosphere and an outlet opening 13 adapted to be connected to the intake manifold (not shown) of an internal combustion motor. Thus air may be drawn through the chamber 11 of the carburetor and mixed with fuel in the desired proportion by means contained within the chamber 11 intermediate the intake opening and the 70 outlet opening.

The outlet opening 13 is formed by a vertically extending tubular portion 14 having a flange 15 at its upper end for connection with the intake manifold. The air intake 12 is cylindrical in form

and extends horizontally in one direction from the bottom of the tubular portion 14. On the opposite side of the tubular portion 14 the body 10 is formed to provide a float or fuel chamber 16. The top wall 17 of the float chamber 16 is preferably removably secured in position by screws 18 and has an aperture 19 (Fig. 1) formed therein adjacent one edge in which aperture a valve device is mounted. The valve device preferably comprises a sleeve 20 having a valve seat 22 at its upper end arranged to be engaged by a valve member 21 slidably mounted in the sleeve. The sleeve 20 has an annular flange 23 formed near its lower end to engage the inner surface of the removable wall 17 and a nut 24 is threaded on the upper end of the sleeve to engage the outer surface of the wall 17 to maintain the sleeve in position. A fitting 25 secured on the outside of the removable wall 17 has an opening 26 adapted for connection with the fuel supply tank (not shown).

The valve member 21 is actuated to maintain a constant level of fuel within the chamber 16 by means of a float 27 mounted on one end of a lever 28, the other end of which is pivoted at 29 on lugs 30 carried by the sleeve 20. The valve member 21 extends downwardly out of the sleeve 20 and has a fork 31 at its lower end providing a horizontal slot which engages a roller 32 carried on the lever 28 between its pivot point and the float 27. Thus the float and valve device comprise a unitary structure which may be removed or adjusted as a unit. To adjust the valve device to maintain different levels of fuel within the chamber 16 shims 33 may be positioned intermediate the flange 23 and the inner surface of the removable wall.

The float chamber 16 is connected, by means hereinafter described, with a fuel discharge member designated generally as 35 positioned within the chamber 11 beneath and in axial alignment with the tubular portion 14 which provides the 115 outlet opening, the fuel discharge member 35 serving to supply fuel to be mixed with air passing through the chamber 11. The passage of air through the chamber 11 is preferably controlled by means cooperating with the discharge member 35 to close or govern the effective size of the outlet opening 13. This means preferably comprises a movable sleeve or throttle 36 supported within the chamber 11 in surrounding relation to the fuel discharge member 35 for movement along a vertical path toward and away from a position in which the outlet opening 13 is substantially closed, this position being such that the carburetor supplies sufficient fuel to run the motor at a low or idling speed.

The sleeve 36 is preferably supported and guided for such movement by means of a trunk piston 37 (Figs. 1 and 2) mounted in a vertical cylinder 38 formed in a housing 39 which extends downwardly from the body 10 in axial alignment with the tubular portion 14. The lower end of the housing 39 is closed by a plate 39a. A plurality of supports 40 formed on opposite sides of the piston 37 extend upwardly in spaced relation and are connected to the sleeve 36. This construction permits the discharge member 35 to be supported in fixed position within the sleeve 36 by means of a bar 41 (Fig. 2) extending between the spaced supports 40 and secured to the bottom of the chamber 11 by screws 42.

The slideable sleeve 36 and the discharge member 35 are preferably formed so that when the sleeve is moved downwardly to its open position, an annular Venturi passage 45 is formed between the fuel discharge member 35 and the sleeve 36

through which air may be drawn by the engine suction. Since this air passes directly by the fuel discharge member, it will be mixed with the fuel and hence constitutes the primary air supply.

As illustrated herein, the outside of the sleeve 36 is formed within an annular projecting portion 48 so that when the sleeve is in its open or lower position or in partially open position, a second annular Venturi passage 46 (Fig. 1) is provided between the sleeve 36 and a sleeve 47 which is positioned within the tubular portion 14 and is shaped to constitute the outer annular wall of the passage. The smallest inner diameter of the sleeve 47 is substantially the same as the greatest outer diameter of the annular portion 48 so that when the slidable sleeve 36 is in its uppermost position as shown in Fig. 2, the venturi 46 will be closed by engagement of the portion 48 with the sleeve 47.

The sleeve 47 is preferably mounted in the tubular portion 14 for sliding movement so that it may be moved downwardly from the position shown in Fig. 1 to the position shown in Fig. 6 to prevent opening of the venturi 46 by downward movement of the sliding sleeve 36. Thus the sleeve 47 serves as a "choke" to cut off the supply of secondary air which normally passes through the venturi 46 and provides a rich fuel mixture suitable for starting or warming up the motor.

The inner surface of the slidable throttle sleeve 36 is of substantially the same diameter from the top down to a point below the projecting portion 48, and then this inner surface slopes inwardly to a throat portion 50 adjacent the lower end of the sleeve and then outwardly so as to form the outer annular surface of the venturi 45, the inner annular surface of which is formed by the fuel discharge member 35.

The fuel discharge member 35 is circular in horizontal cross section and is of greater diameter at substantially the midpoint of its height so that in vertical cross section it is substantially diamond shaped. The member 35 is mounted in the chamber 11 so that when the sliding sleeve 36 is in its uppermost position as shown in Fig. 2, the portion 50 on the sliding sleeve 36 lies opposite the largest portion of the discharge member and leaves a very small annular throat opening 45 (see Fig. 3) through which sufficient air may pass to provide an idling fuel mixture for the motor. From the region of largest diameter the fuel discharge member tapers inwardly and upwardly to provide a gradually increasing annular space between its surface and the inner surface of the sliding sleeve 36. Below this region of largest diameter the fuel discharge member 35 tapers inwardly and downwardly so that during the downward movement of the sliding sleeve 36 the throat of the venturi 45 is always in the plane of the portion 50.

The float chamber 16 is connected with the fuel discharge member 35 by means of a passage comprising a bore 55 formed in the body 10 (Fig. 7), a short substantially vertical bore 56 (Fig. 2), an upwardly inclined bore 57, and a horizontal bore 58 formed in the cross bar 41 which supports the fuel discharge member 35.

The bore 56 has a restricted portion at its lower end forming a valve seat for a needle valve 59 (Fig. 2) positioned within the bore 56 and extending upwardly out of the body 10 to receive an adjusting lever 60 thereon. The adjusting lever 60 has a spring-pressed detent 61 (Fig. 2) thereon engaging notches 62 formed on an arcuate scale 63 so that the fuel supply may be regulated.

As illustrated in the drawings, the cross bar 41 has a stem 65, the lower portion of which is threaded to receive the discharge member. A vertical bore 66 is formed in the stem 65 communicating with the horizontal bore 58 in the cross bar. This vertical bore 66 is flared outwardly at its upper end and the stem 65 is of such a height that the fuel level (Fig. 1) maintained by the float valve is slightly below the open upper end of the stem. As illustrated in Figs. 1, 3 and 4 the fuel discharge member 35 has a vertical central bore 67 in which a plug 68 is fitted. This plug has a conical lower end 69 arranged to project downwardly into the flared upper end of the bore 67 in the stem so as to provide a narrow annular discharge orifice 70 (Figs. 3 and 9) through which fuel may be drawn from the bore 66 in the stem.

Near its upper end the stem 65 is of a smaller diameter than the bore 67 in the discharge member so as to provide an annular passage 71 (Fig. 3) about the stem, and a plurality of openings 72 are formed in the discharge member near the lower end of this reduced portion to admit air into the passage 71. The air admitted through the openings 72 may pass upwardly about the upper edge of the stem 65, and a plurality of ducts 73 extending to the outer surface of the discharge member 35 are provided for the passage of this air out of the fuel discharge member. As the air passes through the openings 72 and past the upper end of the stem 65 fuel is drawn from the annular orifice 70 and is mixed with the air and discharged through some of the ducts 73. During the passage of this air the annular space 74 above the stem 65 serves as a mixing chamber for the fuel and air.

As shown in Fig. 9, the inner ends of the ducts 73 terminate at closely spaced points about the annular mixing chamber 74 so that air drawn out of the chamber 74 through any particular one of the ducts will flow past a small arcuate portion of the fuel discharge orifice 70 so as to draw fuel from that portion. To vary the amount of fuel drawn from the orifice 70 suction is applied to the ducts 73 in varying numbers so that air is drawn along varying numbers of small arcuate sections of the orifice 70 to draw fuel therefrom. This results in a gradual spreading of the mixing action within the chamber 74 and the combustible mixture thus formed passes through the ducts 73 into the venturi 45.

The number of ducts 73 effective as fuel discharge passages is preferably controlled by means of the venturi 45, and to this end the outer ends 130 of the ducts 73 are spaced longitudinally of the axis of the venturi. Thus when the outer end of one of the ducts 73 is positioned above the throat 50 and hence is in the expansion section of the venturi, that end of the duct will be subjected to 135 a pressure which is less than the pressure within the chamber 70 since that chamber communicates with the compression side of the venturi. This causes air to be drawn through the duct. By moving the Venturi sleeve 36 up and down, the number of ducts 73 terminating above the throat 50 may be varied with a resulting variation in the amount of fuel drawn into the mixing chamber 70.

To provide for an idling mixture, one or more of the ducts 73 may terminate above the point of greatest diameter of the discharge member 35 so that the slight amount of air passing through the venturi 45 when the sleeve is in its idling position 140

will draw a small amount of fuel through such a duct.

Thus it will be seen that by varying the number of ducts 73 which terminate at different levels on the discharge member 35 the carburetor may be designed to provide a combustible mixture which will vary in accordance with a predetermined standard set by the size and type of motor with which the carburetor is to be used.

- 10 In Fig. 8, an exemplary distribution or arrangement of the ducts 73 is shown diagrammatically so as to indicate the number of ducts effective as fuel discharge passages for different positions of the Venturi sleeve 36. Thus when the Venturi sleeve 36 is in its upper or idling position so that its throat 50 is positioned at the horizontal line marked "Idling", the outer ends of three of the ducts 73 are positioned above or at the expansion side of the Venturi throat. When the Venturi sleeve 36 is moved downwardly, the number of ducts 73 opening above the throat 50 is increased as indicated by the horizontal lines marking the various positions of the throat 50. Thus when the sleeve is in its lowermost position indicated 25 as "Full throttle" in Fig. 8, all of the ducts 73 open above the throat 50 and are effective as fuel discharge passages.

For the purpose of simplifying the manufacture of the discharge member 35 the plug 68 may be formed with a plurality of longitudinal grooves 75 therein as shown in Figs. 4 and 5. Thus these grooves will cooperate with the sides of the bore 67 in the discharge member 35 to form a part of the ducts 73^a which are similar to the ducts 73 shown in Figs. 1 to 3, and the ducts are completed by a plurality of bores 76 formed in peripherally spaced relation in the discharge member 35 substantially perpendicular to the axis of the vertical bore 67. These bores 76 are formed at different 40 levels so that the carburetor functions the same in this form as in the form illustrated in Fig. 3. It will be noted that in both forms of discharge member, those ducts 73 which terminate at the lower levels are of less length than the other ducts and hence serve to draw more fuel from the annular discharge orifice 70. By using this arrangement it is not necessary to provide as many ducts for varying the mixture in the higher ranges of motor speeds.

- 50 As shown in Fig. 4, two of the horizontal bores 76 formed at different levels on the discharge member may merge or communicate with the same groove 75 so as to increase the suction in the particular groove and thus increase its effectiveness in drawing fuel from the arcuate section of the fuel discharge orifice.

The sliding sleeve 36 is moved up and down by means of a lever 77 mounted within the housing 39 on a shaft 78 which extends through and is journaled in the walls of the housing. The outer end of the lever 77 is connected to the piston 37 by means of a link 79. An arm 80 is secured on the shaft 78 (Fig. 2) outside of the housing 39 for connection to a suitable foot pedal or manual actuating device (not shown). As will be apparent from Fig. 1, the lever 77 will be in a substantially vertical position when the sliding sleeve 36 is in its upper or idling position and when the manual operating device (not shown) is moved at a given rate, the sliding sleeve 36 will be moved downwardly at a comparatively slow rate at first since the vertical component of a given arcuate movement of the arm 77 will be small when the arm is near its vertical position. As the sleeve 36 approaches

its open position its rate of movement will increase materially relatively to the rate of movement of the manual actuating device since the arm 77 will then be near its horizontal position as shown in Fig. 1 and the vertical component of a given arcuate movement will be comparatively large.

Thus this actuating mechanism enables the operator to control more accurately the fuel mixture and the resulting acceleration of the motor in its lower range of speeds. An adjustable stop device in the form of the bolt 81 is positioned in the wall of the housing 39 to engage the lever 77 and limit the upward movement or idling position of the sliding sleeve 36.

A similar operating device is provided for the sliding choke sleeve 47, this operating device comprising a lever 82 mounted on a horizontal shaft 83 extending through and journaled in the air intake 12 and having an operating lever 84 on its outer end which may be connected to a suitable operating wire 85. The outer end of the lever 82 is connected to the sliding choke sleeve by a link 86 and the upward movement of the sleeve 47 is limited by an adjustable stop 87 mounted in the body 10 in the path of the upper end of the link 86.

In order that the sliding throttle sleeve 36 may be more accurately and easily controlled by the operator, means is provided for counteracting the tendency of the sliding sleeve 36 to be moved upwardly by the action of the motor suction. This means preferably includes the piston 37 and the cylinder 38 which support and guide the sliding sleeve 36. A passage 89 formed in the body 10 extends from the cylinder 38 upwardly through the body and opens into the tubular portion 14 which forms the outlet opening of the carburetor, a longitudinal slot 90 being formed in the choke sleeve 47 so that in all positions of the sleeve 47 the cylinder 38 communicates with the same suction source that tends to move the sliding sleeve 36 upwardly. Thus by properly proportioning the size of the piston 37 and the cylinder 38 an equalizing force is applied to the moving parts so that the operator may more easily and accurately control the movement of these parts.

In the operation of the carburetor on a motor, the motor is provided with a rich starting mixture by lowering the choke sleeve 47 by means of its operating lever so that when the sliding sleeve or throttle 36 is lowered, (Fig. 6) the secondary air passage through the venturi 46 will remain closed. With the sliding throttle sleeve 36 in its lowered position and the secondary air cut off, the motor is turned over by the starter to draw air through the venturi 45. The throat 50 of the venturi being then positioned beneath certain of the ducts 73, those ducts will function as fuel passages to draw fuel from the annular orifice 70. At the same time air will be drawn into the annular passage 71 through the openings 72 and upwardly past substantially the entire length of one side of the orifice 70 to draw fuel into the mixing chamber 74 where it will be well mixed with the air to provide a rich fuel mixture which is discharged into the venturi 45 through the ducts 73. In the venturi 45 the mixture is made slightly more "lean" by the primary air passing therethrough and is then passed from the outlet 14 to the motor.

When the motor has been started and warmed up by the rich fuel mixture thus provided, the choke sleeve 47 and the sliding throttle sleeve 36 may be raised to their normal or idling position

shown in Fig. 2 wherein most of the ducts 73 lie below the Venturi throat 50 and are therefore ineffective as fuel discharge passages. While the parts are in this idling position, fuel in smaller quantities is drawn into the mixing chamber 74 through a few small arcuate sections of the orifice 70 and is there mixed with air in substantially the same manner as when the carburetor is choked, the ducts 73 opening above the Venturi throat 50 being the only ones which act as fuel discharge passages. The other ducts 73 lying beneath the Venturi throat 50 may then supply air to the mixing chamber 74 in a manner similar to the operation of the openings 72 at other times.

When it is desired to accelerate the motor, the sliding sleeve 36 is moved gradually downwardly to position the Venturi throat beneath the ducts 73 in gradually increasing numbers so as to bring them into play as fuel discharge passages and cause fuel to be drawn through a greater number of small arcuate portions of the orifice 70. During this movement the inner venturi 45 is opened to permit passage of a larger amount of primary air, and the outer venturi 46 is opened to permit the passage of secondary air.

As the ducts 73 are brought into active play as fuel discharge passages the mixing chamber 74 continues to function in the same manner as it did while the motor was idling, this condition being changed only at the very highest motor speeds wherein the sliding sleeve 36 is positioned so that the openings 72 are above the Venturi throat 50. When this condition obtains, these openings will also serve as fuel discharge passages due to the great suction applied thereto by the motor.

If it is desired to reduce the amount of secondary air admitted, the adjusting stop 87 may be screwed inwardly to change the normal position of the sleeve 47 and thus reduce the size of the venturi 46.

During the operation of the carburetor, the equalizing means renders the throttle sleeve 36 more easily movable so that the motor may be accelerated very smoothly. The use of the crank 77 as a throttle operating means also serves to facilitate the gradual and accurate movement of the throttle sleeve 36 to provide for more gradual acceleration of the motor in its lower ranges of speed.

From the foregoing it will be apparent that the invention provides a carburetor which may be economically manufactured since it is formed from a comparatively small number of parts which may easily be assembled. It will also be seen that the carburetor will be efficient in operation by reason of the simplicity and accuracy of the adjustments provided for varying the fuel mixture and also by reason of the accurate throttle control provided by the actuating connection which embodies a crank.

It will also be evident that the carburetor is of such a construction that the parts may be easily designed and constructed to provide a combustible mixture which varies in richness in accordance with a predetermined standard determined by the size and type of motor with which it is to be used. The carburetor herein disclosed also makes it possible to obtain a more gradual and smooth acceleration of the motor, since it operates on the same principle when it is choked, when it is idling, and when it is being accelerated through the lower ranges of speed.

The means provided for equalizing the forces exerted on the throttle sleeve renders the throttle sleeve more easily and accurately controllable and thus make it possible more smoothly to accelerate the motor.

I claim as my invention:

1. A carburetor having, in combination, a hollow body, having inlet and outlet openings, a member mounted within said body having a fuel supply duct with an upwardly opening narrow annular orifice within the member, there being an annular fuel mixing chamber in the member and into which said orifice opens, there also being a plurality of fuel discharge ducts in said member with the inner ends opening into said chamber closely adjacent to and annularly spaced about said orifice and leading outwardly from said chamber and opening at different levels and at peripherally spaced points on the outside of said member, said member being shaped to form the inner annular side of an annular venturi through which air is drawn during operation of the carburetor, a sleeve surrounding said member shaped to form the outer side of the venturi, and means for moving one of the Venturi parts to move the throat of the venturi past the ends of said ducts to cause suction of fuel from said ducts when said ducts are at the expansion side of said throat.

2. A carburetor having a hollow body with inlet and outlet openings, a fuel discharge member mounted within said body, said member having an annular chamber formed therein and an annular fuel discharge orifice opening upwardly into said chamber, said member having a passage through which air may pass upwardly past one edge of said orifice into said chamber, there being a plurality of ducts in said member with their inner ends opening into said chamber adjacent to and at annularly spaced points about said orifice and with their outer ends opening at different levels on the outer surface of said member, an annular control member surrounding said discharge member and cooperating to form a Venturi passage therebetween, and means to adjust said members relatively to each other to vary the position of the throat of the venturi with respect to the outer ends of said ducts.

3. In a carburetor, the combination of a hollow body having air inlet and outlet openings, two members mounted in said body forming the inner and outer sides of an annular venturi through which air is drawn during operation of the carburetor, a fuel supply, there being a plurality of fuel discharge ducts formed in one of said members connected to said fuel supply and opening into said venturi at points spaced longitudinally of the venturi, the other of said members being movable to vary the position of the Venturi throat relatively to said ducts so that fuel may be drawn through varying numbers of said ducts in accordance with the position of the Venturi throat relatively thereto, said ducts being of different lengths as determined by the amount of fuel which it is desired to draw therethrough.

4. In a carburetor, the combination of a hollow body having inlet and outlet openings, two members mounted in said body forming the inner and outer sides of a venturi through which air is drawn during operation of the carburetor, a plurality of fuel discharge ducts formed in one of said members and opening into said venturi at points spaced longitudinally of the venturi, one of said members being movable to vary the position of the Venturi throat relatively to said ducts.

so that fuel may be drawn through said ducts in varying numbers as they are positioned at the expansion side of the Venturi throat.

5. In a carburetor having a hollow body with 5 inlet and outlet openings, a fuel discharge member within said body, a sleeve surrounding said member and forming a Venturi passage through which air is drawn during operation of the carburetor, there being a duct in said member having intake and discharge ends communicating with said venturi at points spaced longitudinally thereof, means arranged to discharge fuel into said duct when air is drawn therethrough, said sleeve being longitudinally movable to position the throat thereof intermediate the intake and discharge ends of said duct to cause air to flow therethrough, said sleeve also being movable to a position wherein both ends of said duct are at the same side of said throat so as to prevent flow 10 of air through said duct toward the discharge end thereof.

6. In a carburetor, the combination of a body 25 providing a fuel supply, a primary air passage arranged initially to mix the air passing therethrough with said fuel, and a secondary air passage arranged to mix the air passing therethrough with the fuel mixture formed by the fuel and primary air, a single annular throttle member operable for controlling the quantity of fuel and primary and secondary air, and a second annular 30 control member arranged to be moved relatively to said throttle member to vary the effect of said throttle member on the secondary air supply for the purpose of providing a rich fuel mixture for starting.

35 7. In a carburetor, the combination of a body providing a fuel supply, a primary air passage arranged initially to mix the air passing therethrough with said fuel, and a secondary air passage arranged to mix the air passing therethrough with the fuel mixture formed by the fuel and primary air, a single annular throttle member operable for controlling the quantity of fuel and primary and secondary air, and a second control member operable to cut off or reduce the supply 40 of said secondary air for the purpose of providing a rich fuel mixture for starting.

45 8. In a carburetor, the combination of a fuel discharge member having a mixing chamber formed therein, a first Venturi member, there being a plurality of ducts in said fuel discharge member leading from said mixing chamber into said Venturi member, said ducts being operable to discharge fuel from said mixing chamber into 50 said venturi or to admit air from said venturi into said mixing chamber, and a second Venturi member surrounded by said first Venturi member actuatable to control and vary the number of ducts acting to discharge fuel from the mixing chamber into said venturi.

55 9. A fuel discharge member for carburetors comprising, in combination, a body having a bore therethrough, a stem extending into the lower end of said bore having a vertical passage opening upwardly through which fuel may be conducted into said bore, a plug extending downwardly into the upper end of said bore having a conical lower end extending into said passage to form an annular fuel orifice, said plug cooperating with said stem and the wall of said bore to provide a mixing chamber within the body, said stem being of reduced size near its upper end to provide an annular space between it and said bore, said body having a plurality of openings 60 through which air may pass into said space below

said chamber and then upwardly into said chamber, and a plurality of fuel discharge ducts leading from said chamber to the outside of said body, said ducts being formed by a plurality of longitudinal grooves formed in the outer surface of 80 said plug and extending upwardly from said mixing chamber and a plurality of bores formed in said body at circumferentially and longitudinally spaced points and communicating at their inner ends with the passages formed by said longitudinal slots.

10. A fuel discharge member for carburetors, comprising, in combination, a body of circular horizontal cross-section tapering inwardly from its mid-point toward its top and bottom, said body having a bore therethrough, means extending into the lower end of said bore through which fuel may be conducted into said bore, a plug extending downwardly into the upper end of said bore and operating with said fuel conducting means and the wall of said bore to provide a mixing chamber within the body, there being a plurality of fuel discharge ducts leading from said chamber to the outside of said body, said ducts being formed by a plurality of longitudinal 100 grooves formed in the outer surface of said plug and extending upwardly from said mixing chamber to form passages closed at their upper ends, and a plurality of substantially horizontal bores formed in said body at circumferentially and longitudinally spaced points each communicating at its inner end with the passage formed by one of said longitudinal slots, the majority of said horizontal bores being formed so as to open on the inwardly tapered bottom portion of the 110 body.

11. A fuel discharge member for carburetors, comprising, in combination, a body having a bore therethrough, means extending into the lower end of said bore through which fuel may be conducted into said bore, a plug extending downwardly into the upper end of said bore and cooperating with said fuel conducting means and the wall of said bore to provide an annular mixing chamber within the body, and a plurality of fuel discharge ducts leading from said chamber to the outside of said body, said ducts being formed by a plurality of longitudinal grooves formed in the outer surface of said plug and extending upwardly from said mixing chamber and a plurality of bores formed in said body at circumferentially and longitudinally spaced points and communicating at their inner ends with the 120 passages formed by said longitudinal slots.

12. A fuel discharge member for carburetors comprising, in combination, a support, a stem extending upwardly therefrom having a vertical fuel passage therein, a body having a bore therethrough and mounted with said bore fitting about said stem, a plug in said bore above said stem having a conical lower end extending into the fuel passage in said stem to define an annular fuel discharge orifice within said bore and to provide an annular mixing chamber within the bore above the orifice, openings in said body below said chamber through which air may pass into said chamber, and a plurality of fuel discharge ducts extending from said chamber and opening to the outside of said body at different levels thereon.

13. The combination with a carburetor having a movable throttle member operable to control the speed of a motor and to vary the speed from low to high, of means for actuating said member throughout its range including a crank arm 15

having its outer end connected to said member so that in the lower ranges of motor speeds said end moves substantially transversely of the path of movement of said member while in the upper 5 ranges of speed said end moves substantially parallel to said path.

14. A carburetor having, in combination, a hollow body having an air inlet opening in one side thereof and an outlet opening in the top thereof 10 adapted for connection with a motor, a housing formed on said body on the lower side thereof in alinement with said outlet opening, said housing having a cylinder formed therein opening upwardly into said body, a fuel discharge member 15 supported within said body centrally of said outlet opening and extending across the open end of said cylinder so as to leave an opening on each side of the fuel discharge member, an annular throttle member surrounding said fuel discharge 20 member and cooperating therewith when in one position to substantially close said outlet opening, and means for supporting and guiding said throttle member for movement toward and away from its closed position, said means comprising 25 a piston slidably mounted in said cylinder and a pair of supporting members connected to said piston on opposite sides and extending upwardly on opposite sides of said fuel discharge member and connected to said throttle member.

30 15. A carburetor having, in combination, a hol-

low body having an inlet opening and an outlet opening adapted for connection with a motor, fuel discharge means supported within said body, a manually operable throttle member for closing or varying the effective area of said outlet opening, the suction of the engine tending to move said throttle toward its idling position, means for supporting and guiding said throttle member comprising a cylinder in said body, a piston in said cylinder upon which piston said throttle member is mounted, and means providing a passage connected at one end to said cylinder on the side opposite from said throttle member and opening at its other end into said outlet opening substantially to equalize the suction on said throttle and reduce the effort necessary to open the throttle manually.

16. In a carburetor having a manually movable control member positioned in a suction passage so that the suction tends to move said member toward its idling position, the combination of a piston and cylinder device having one of its parts fixed and the movable part connected to said manual control member, and a connection between said cylinder and the said suction passage 100 on the motor side of said member so that said device applies an equalizing force to said member and permits it to be moved manually with little effort.
